FIG. 1

Des. 189,019

PAGE 2

Fig. 3

Fig. 1 is a view in side elevation of a combination carpet and floor sweeper embodying my new design; Fig. 2 is a view in front elevation; and

Fig. 3 is a top plan view thereof.

The handle is shown broken away in Figs. 1, 2 and 3 for convenience of illustration.

The rear and other side of the sweeper are substantially like the respective front and side shown.

I claim:

The ornamental design for a combination carpet and floor sweeper, substantially as shown and described.
